UNITED STATES PATENT OFFICE

WILLIAM S. HAMM, OF ELKHART, INDIANA, ASSIGNOR TO THE ADLAKE COMPANY, OF CHICAGO, ILLINOIS, A CORPORATION OF ILLINOIS

SASH CONSTRUCTION

Application filed January 31, 1929. Serial No. 336,379.

Metallic window structures are in many respects superior to wooden window structures. They are strictly fireproof; are much stronger; will not warp, shrink or swell; 5 occupy less space; and will last considerably longer. They are, however, a little too heavy for some classes of installations where lightness in weight is a controlling factor. Metallic window structures made of sheet aluminum would not be too heavy for such installations, but no commercially satisfactory aluminum window structure of the sliding sash type—which is the type in greatest demand—has heretofore been produced owing 10 to the fact that when an aluminum sash is slid up and down in a closely fitting aluminum guide the stiles of the sash stick, scuff up and wear out very rapidly.

The object of the present invention is to 20 provide a novel aluminum window structure of the sliding sash type which is not subject to rapid wear, will not stick or scuff up, and will give excellent service for a long period of time.

25 While the foregoing statement is indicative of the nature of the invention, other objects and advantages will be apparent to those skilled in the art upon a full understanding of the construction, arrangement 30 and operation of the improved sash and guide structure.

Two slightly different embodiments of the invention are presented herein for the purpose of exemplification, but it will of course 35 be appreciated that the invention is capable of being incorporated in various other forms coming equally within the scope of the appended claims.

In the accompanying drawings:

40 Fig. 1 is a fragmentary face view of an aluminum sash and guide assemblage constructed in accordance with the invention;

Fig. 2 is a horizontal section through the 45 cooperating portions of the sash and guide, taken on the line 2—2 of Fig. 1; and

Fig. 3 is a section corresponding generally to Fig. 2, showing a slightly different embodiment of the invention.

The window structure shown in Figs. 1 50 and 2 includes a sash 10 in which the rails

and stiles 11 and 12 are made of sheet aluminum. Each stile of the sash slides up and down in a guide 13, which guide consists of a fixed strip 14 which is made of sheet aluminum and a removable strip 15 which is also 55 made of sheet aluminum. The fixed strip 14 is fastened to the jamb 16 of the associated window casing by means of a number of screws 17, and is characterized by a central web portion 18 in spaced relation to the jamb, two leg portions 19 and 20 which extend from the edges of the web portion into engagement with the jamb, and two reversely bent flange portions 21 and 22 which extend 60 from the inner edges of the leg portions outwardly in slightly spaced relation to the same.

The flange portion 22 of the fixed strip terminates preferably a little short of the plane of the web portion 18, and the removable strip 15—which will hereinafter be referred to as 70 the sash-retaining strip—is positioned partly within the groove 23 which is formed in the fixed strip between the portions 20 and 22 thereof. The sash-retaining strip is detachably secured to the fixed strip by means of a 75 number of rivets or screws 24 which extend crosswise of the groove 23 at regular intervals and engage within bayonet slots 25 formed in the inner edge of the sash-retaining strip.

The flange portion 21 of the fixed strip extends considerably beyond the plane of the web portion 18, and provides a substantially rigid backing for a lining strip 26 of a relatively soft non-metallic material, such as 85 cork, felt, wood, leather, fiber, asbestos, fabric, and the like, which lining strip extends into the groove 27 which is formed in the fixed strip between the portions 19 and 21 thereof and is held against outward displacement by means of an inturned flange 28 on the outer edge of the portion 21. One face of the stile of the sash bears directly against the lining strip, and, when the sash is moved up and down in the guide, the lining strip absorbs 90 all of the wear and prevents that face of the stile from wearing out.

Another lining strip 29 is carried by the sash-retaining strip in spaced parallel relation to the lining strip 26. The sash-retain- 100

ing strip forms a backing for the lining strip 29 and is provided with an offset portion 30 in which the lining strip is held against displacement. The lining strip 29 is made of the same material as the lining strip 26 and performs the same function with respect to the other face of the stiles with which it is in direct engagement.

As the lining strips become more or less worn away or compacted as a result of continued service, the outer portion of the sash-retaining strip is automatically advanced toward the flange portion 21 of the fixed strip by means of a spring strip 31, which spring strip is secured to the inner portion of the sash-retaining strip and presses resiliently against the outer wall of the groove 23 in the fixed strip in such a way as to move the outer portion of the sash-retaining strip in the desired direction.

The sash and guide assemblage shown in Fig. 3 differs primarily from that shown in Figs. 1 and 2 in that two sash 32 and 33 are employed instead of one and a single guide 34 accommodates both of the sash. In the guide 34, the two web portions 35 and 36 correspond to the web portion 18, the two flange portions 37 and 38, which are bridged together, correspond to the flange portion 21, and the two sash-retaining strips 39 and 40 correspond to the sash-retaining strip 15. The flange portions 37 and 38 back up lining strips 41 and 42 which are held in place thereagainst by the edges of a cap strip 43 secured to the web portion 44 which bridges such flange portions, while the outer portions of the sash-retaining strips 39 and 40 back up lining strips 45 and 46.

The form of attachment of the lining strips is preferably such as to facilitate replacement of the same. In both of the structural embodiments herein shown, the lining strips are preferably made of a material such as cork, leather, fabric or the like which is sufficiently flexible to permit them to be bowed and then snapped into position. If a less flexible material is employed for the lining strips, and it is desired to have the strips readily replaceable, suitable changes should be made in the construction of the backing elements for the same.

I claim:

1. A sash guide, comprising a sheet metal strip which is adapted to be fixedly attached to the jamb of a window frame, another sheet metal strip which is adapted to be detachably secured to the first mentioned strip, and a strip of relatively soft non-metallic material which is substantially co-extensive in length with the detachable strip and is positioned against the latter for sliding coaction with a sash in the guide, said detachable strip being provided with laterally spaced grooves in which the side edges of the non-metallic strip are held.

2. A sash guide, comprising a sheet metal strip which is adapted to be fixedly attached to the jamb of a window frame, another sheet metal strip which is adapted to be detachably secured to the first mentioned strip, and a strip of relatively soft non-metallic material which is substantially co-extensive in length with the detachable strip and is positioned against the latter for sliding coaction with a sash in the guide, said detachable strip being provided with a reversely bent flange behind which one edge of the non-metallic strip is clamped. 70

3. A sash guide, comprising a sheet metal strip which is adapted to be fixedly attached to the jamb of a window frame, another sheet metal strip which is adapted to be detachably secured to the first mentioned strip, and a strip of relatively soft non-metallic material which is substantially co-extensive in length with the detachable strip and is positioned against the latter for sliding coaction with a sash in the guide, said detachable strip being provided with a recess in which the non-metallic strip is fastened. 75

4. In a metallic window structure, the combination with a sheet metal sash member, and a sheet metal guide member in which the sash member slides, of a sheet metal strip attached to one of said members, and a strip of soft yieldable non-metallic material carried by said metal strip in slightly projecting relation thereto for sliding coaction with the other of said members, said metal strip having a reversely bent portion of less projection than the non-metallic strip which forms a pocket in which one edge of the non-metallic strip is clamped. 80

5. In a metallic window structure, the combination with a sheet metal sash member, and a sheet metal guide member in which the sash member slides, of a sheet metal strip attached to one of said members, and a strip of soft yieldable non-metallic material carried by said metal strip in slightly projecting relation thereto for sliding coaction with the other of said members, said metal strip having laterally spaced reversely bent portions of less projection than the non-metallic strip which forms pockets in which both the edges of the non-metallic strip are clamped. 85

6. A sash guide, comprising a sheet metal strip which is adapted to be fixedly attached to the jamb of a window frame, another sheet metal strip which is adapted to be detachably mounted in spaced parallel relation to the first mentioned strip, and a strip of relatively soft non-metallic material which is substantially co-extensive in length with the detachable strip and is positioned against the latter for sliding coaction with a sash in the guide, said detachable strip being provided with a reversely bent flange behind which one edge of the non-metallic strip is clamped. 90

7. A sash guide, comprising a sheet metal strip which is adapted to be fixedly attached to the jamb of a window frame, another sheet metal strip which is adapted to be detachably mounted in spaced parallel relation to the first mentioned strip, and a strip of relatively soft non-metallic material which is substantially co-extensive in length with the detachable strip and is positioned against the latter for sliding coaction with a sash in the guide, said detachable strip being provided with a recess in which the non-metallic strip is fastened.

8. A sash guide, comprising a sheet metal strip which is adapted to be fixedly attached to the jamb of a window frame, another sheet metal strip which is adapted to be detachably mounted in spaced parallel relation to the first mentioned strip, a strip of relatively soft non-metallic material which is substantially co-extensive in length with the detachable strip and is positioned against the latter for sliding coaction with a sash in the guide, and spring means for pressing the strip of soft material resiliently against the face of the sash.

In witness whereof I have hereunto subscribed my name.

WILLIAM S. HAMM.
